Attorney

UNITED STATES PATENT OFFICE.

GEORGE M. PEABODY, OF HYDE PARK, MASSACHUSETTS, ASSIGNOR TO E. E. TAYLOR COMPANY, OF BOSTON, MASSACHUSETTS, A CORPORATION OF MASSACHUSETTS.

VENTILATED INSOLE.

Application filed July 6, 1925. Serial No. 41,569.

My present invention is a novel and improved ventilated shoe construction, and includes a novel method or process of making the same.

Heretofore many attempts have been made to construct ventilated footwear of varying capacity, style and construction, but such prior articles have been objectionable for various reasons. Many attempted ventilated shoe constructions have been impractical from the manufacturing standpoint, or have involved extremely difficult and such expensive methods, materials and machines as to render them uncommercial. Other objections have been the entire change in shoe manufacturing methods required to carry out the construction required.

In my present process I am enabled to utilize the present standard and well known shoe manufacturing processes with but slight changes and therefore my process results in the production of a commercially practicable shoe with economical machine operations and without employing specially skilled help.

An important feature of my invention consists in the provisions of a ventilated insole and a combined arch supporting cushion and absorbent member. Further features consist in the provision of a smooth heel seat in the interior of the shoe in combination with the ventilated insole structure and the resulting shoe gives the benefit of ventilation, arch supporting, yielding instep or arch cushion, and smooth heel seat and a high grade and preferably welt shoe construction.

A further feature of the present invention consists in the novel insole utilized. My improved insole being first prepared to include the ventilating and cushioning features as well as to incorporate also the nailless heel seat feature, so far as the heel contacting surface of the insole is concerned.

Further features of the invention, novel combinations and the method of making same will be more fully pointed out and claimed.

Referring to the drawings, illustrating a preferred embodiment wherein my novel ventilated shoe incorporates the new insole and is made in accordance with my present method of construction,

Fig. 1 is a side view of the shoe with a

portion of the shank and heel broken away and shown partly in cross-section;

Fig. 2 is a fragmentary plan view of the foot-contacting surface of the insole;

Fig. 3 is a fragmentary view showing a portion of the heel construction in cross-section illustrating the nailless heel seat method of manufacture;

Fig. 4 is a longitudinal cross-sectional view of my novel insole shown as an insole for welt shoes;

Fig. 5 is a plan view of the insole from the channel or ribbed side;

Fig. 6 is a cross-sectional view on the line 6—6 of Fig. 5; and

Fig. 7 is a cross-sectional view on the line 7—7 of Fig. 5.

Referring to the drawings wherein I have illustrated a welt shoe construction embodying my invention, the shoe upper designated generally at 1 may be of any suitable style, form or contour and the shoe is made on any desired type or style of last. 2 indicates the outsole, 3 the welt, I preferably employing usual welt shoe construction so far as lasting, inseaming and sole attaching is concerned. In making my shoe I first prepare a novel form of insole, designated at 5, wherein I provide a plurality of openings or recesses to give ventilation, as shown at 6, 6, 6. These holes may be as numerous as desired and of any desired size and are intended to lead directly from the foot contacting surface of the insole 5 through the same, and into the absorbing and cushioning member 7, positioned on the under side of the insole and—as in the case of a welt insole—between the sewing rib 10. As herein illustrated a usual sewing rib construction is shown wherein two portions of the insole 5 are cut at the margin and turned upwardly for uniting into the composite rib 10. Preferably also this insole may be "gemmed", i. e., reinforced with a canvas layer 12 which may likewise extend into and be cemented with the composite rib 10.

The ventilating openings 6, 6, extend entirely through the canvas layer 12 to afford an opening or access completely through that portion of the insole which is thus perforated, as clearly shown in Figs. 4 and 6. I may apply the cushioning and absorbent layer 7 to the insole before the latter is assembled on the last for incorporation in

the shoe, or I may apply the same after the shoe is lasted or even after the lasted shoe has been subjected to the inseam stitching operation. Preferably, however, I prepare the insole as a complete article, either with or without the gemming reinforcement 12, but with the cushioning and absorbent layer 7. Furthermore I complete the preparation of the insole by splitting the heel portion as shown at 15, giving an upper heel contacting layer 17 and a lower layer 18 which latter is to receive the heel nails 19, 19, to be clinched therein when the heel 20 is applied, a clinching plate 21 being interposed between the two layers to preserve the "nailless" heel seat surface 17.

With the insole thus prepared, I then apply the plate 21 fitting same between the two split portions 17 and 18 of the heel end of the insole. This plate 21 acts as a clinching plate for the heel nails, both for lasting the heel seat and for clinching the heel holding nails. Thereupon I assemble the insole and upper on a last, last the shoe in the usual manner, unite the welt 3, upper 1 and insole rib 10 by the usual inseaming machine, apply such filler as may be necessary over the forepart of the insole;—the cushioning and absorbent mass 7 taking the place of a filler over the perforated portion; and thereupon I apply the outsole and unite same to the shoe. Thereupon the heel 20 is applied and the nailing operation effected, clinching the nails against the plate 21, whereupon the last is pulled, the plate 21 is removed and the upper layer 17 replaced and cemented in position if desired. Thus I complete my ventilated, cushioning, and nailless heel seat shoe construction without extra machines, devices or special or difficult operations.

The action of the foot in walking over the cushioning material 7 acts largely to produce a suction through the ventilating recesses 6, as well as to normally absorb any moisture on the insole. The material 7 may be of any desired or suitable mass or character, as well as height if desired to give an arch supporting effect. Preferably I utilize felt or other absorbent material which may be readily cut to size and applied to and secured upon the desired portion of the insole by any adhesive. In a welt shoe it can fit readily between the shank and forepart sections of the sewing rib, while in a McKay shoe the cushioning and absorbent material would simply be attached on the inner side of the insole at the ventilated portion. 55

My invention is further described and defined in the form of a claim as follows:

A prepared insole for use in the manufacture of welt boots and shoes, having, in combination, a sewing rib around its marginal edge forwardly of the heel portion, a fabric reinforcing layer secured to the insole and to the sewing rib and occupying the space enclosed by said sewing rib, a plurality of perforations extending through the insole and through the reinforcing layer and located only at the shank portion of the insole, and an imperforate layer of yielding and absorbent material secured to the reinforcing layer and to the insole and located at the shank portion only of the insole, said imperforate layer of yielding and absorbent material being of sufficient thickness to act as an arch support. 60 65 70 75

In testimony whereof, I have signed my name to this specification.

GEORGE M. PEABODY.
